HUBERT CLAUS, OF THALE-IN-THE-HARZ, GERMANY.

MACHINE FOR ENAMELING SHEET METAL, &c.

SPECIFICATION forming part of Letters Patent No. 465,461, dated December 22, 1891.

Application filed August 26, 1891. Serial No. 403,748. (No model.)

To all whom it may concern:

Be it known that I, HUBERT CLAUS, a resident of Thale-in-the-Harz, Empire of Germany, have invented an Improved Machine 5 for Enameling Sheet Metal and other Substances, of which the following is a specification.

This invention relates to a new machine for spreading liquid enamel or other analogous 10 liquid or semi-liquid matter upon plates of sheet metal or other substances and upon sundry other surfaces.

The main use to which my invention can be put is to spread enamel upon metallic plates 15 for the manufacture of enameled sign-boards and to avoid hand labor and to insure a greater uniformity in the coating of enamel, and therefore a better quality of sign.

The invention consists of a new combination 20 and arrangement of parts hereinafter more fully specified, and pointed out in the claims.

In the accompanying drawings, Figure 1 represents a vertical longitudinal section of 25 my improved enameling-machine, the line 1 1, Fig. 3, indicating the plane of section. Fig. 2 is a detail vertical section on the same line of the upper part of the machine and is on a larger scale than Fig. 1. Fig. 3 is a plan or 30 top view of the machine, parts being broken away. Fig. 4 is an enlarged plan or top view, partly in section, of one end of the upper portion of the machine. Fig. 5 is an enlarged and somewhat exaggerated bottom view of 35 the valve portion on the lower end of the hopper.

The letter A in the drawings represents the main lower framing of the machine. In this frame are the bearings for two parallel shafts 40 B and C, each carrying a pair of sprocket-wheels a a, over which sprocket-wheels endless chains d d are placed. These chains are represented in Fig. 3 by double dotted lines and in Fig. 1 by single heavy dotted lines. 45 The two endless chains d d are connected by slats e, made of wood or analogous substance and riveted or otherwise tied to the chains, and over these slats e is placed an endless band or apron f of wire-gauze or analogous 50 fabric. All these parts are arranged to constitute an endless carrier for the plates or articles to be enameled, said carrier being put

in motion whenever rotary motion is imparted by a belt g to a pulley on the shaft C from a suitable driving-pulley h.

55

Suitable idle-wheels i are hung in the framing A at proper intervals to support the chains d and apron f in a substantially horizontal position during their passage from one sprocket-wheel to the other. A suitable brush j is 60 placed beneath the apron f to remove from its surface any enamel which may adhere thereto. The lower frame A supports at or near its center an upwardly-extending framework D, which is composed, mainly, of four 65 posts k, that are braced together by horizontal braces l and m, and that rest with their lower ends on bolsters n, that are formed on the frame A. By means of screws E or analogous mechanism the entire central framework D may be raised more or less, for purposes hereinafter more fully described. The 70 above-mentioned upwardly-extending framework D carries at its upper portion a funnel-like vessel F, within which is contained a perforated false bottom G, below which false bottom the vessel F contains a stirrer-wheel H and below that a longitudinal slit or outlet-opening o. Directly above the central semi-cylindrical depression of the perforated false 75 bottom or sieve G the funnel F contains a rotary brush I. Beneath the central slit or outlet o are two rubber blades p p, which, as Fig. 2 more clearly indicates, can have their lower ends brought into close proximity with 80 one another to constitute a narrower, or, when desired, a wider, outlet for the liquid enamel. These blades, which are made of india-rubber 85 or analogous substance, have affixed to their outer sides short plates q q, which are 90 arranged at about equal distances apart, as indicated by dotted lines in Fig. 3, and as also indicated in Figs. 4 and 5. Each plate q connects by a link r with a crank s, whose hub embraces a shaft J, said hub carrying a counterpoise t. The hub of each crank s and counterpoise t can be clamped onto the shaft J by 95 screws w; but by unfastening said screws the said hub will remain loose on the shaft J and the counterpoise t will press its plate q inward, so as to crowd the rubber lips or valves p together at that place. A shaft L, which is 100 hung in the frame D and has a hand-wheel x, has right and left screws y, which gear into

worm-wheels z , that are mounted upon the shafts $J J$, so that by turning the hand-wheel x the shafts $J J$ on opposite sides of the funnel will be turned in opposite directions, and with them the hubs of those cranks s that are clamped tight to said shafts by their screws w . Thus when all the cranks s , together with their counterpoises, are tightly clamped by the screws w to the shafts J the turning of the right and left screws of L will open or shut the valves p uniformly throughout their length; but when some of the cranks s are left loose on said shafts, then those which are loose will hold their portions of the flexible valves p in a substantially closed position, while those which are fast will be able to draw their portions of said flexible valves farther apart. This is indicated by Fig. 5. Hence I am enabled by this arrangement to open the outlet from the funnel F more or less throughout its length, or to open said outlet more or less at certain intervals of its length. Beneath the outlet thus formed by the valves p are hung in the framing D two rollers $M M$, whose shafts lie in slotted bearings, and can, by screws a^2 , (see Fig. 4,) be set more or less apart or more or less closely together. The shafts of these rollers $M M$ are geared together at one side of the machine, as indicated at b^2 in Fig. 3, so that as rotary motion is imparted to one by belt d^2 from the driving-shaft h said motion will be transmitted in opposite direction to the other of said rollers.

Beneath each roller M is a scraper N , as clearly shown in Fig. 2, and underneath these scrapers there is placed an inclined blade O , which is vertically adjustable in a supporting-bracket P and which can be tilted more or less in said bracket. Rotary motion can be imparted to the brush I by a belt e^2 from the shaft h and to the stirrer H by a belt f^2 from the driving-shaft h . Of course, instead of connecting the driving-shaft by belts in the various contrivances to be rotated, other means of communicating the desired motion may be employed.

Having now described the general construction of my machine, I will proceed to state its operation: The liquid or semi-liquid enamel is put into the funnel F and flows, owing to its gravity and liquid character, through the sieve G . If, however, any part of the enamel should be too thick to pass through said sieve it will be retained by the same and gradually flow underneath the rotary brush I , which will reduce the thick matter and force it through the sieve. The liquid matter passing underneath the sieve G is therefore of uniform consistency and will gather in the rounded lower part of the funnel, where it is exposed to the rotary agitator H , which prevents the solid particles of the enamel from becoming separated or settling in the liquid parts and from becoming too consistent or lumpy. The enamel gathering in the lower part of the funnel is now free to escape through the opening o and between the valve-

like blades p , which latter are adjusted a desired distance apart, either throughout their entire length or at intervals, so as to allow a given quantity of enamel to flow between them during a given period of time. If the enamel is not to escape through the entire length of the slots formed between the valves p , these valves can be kept closed altogether at or near the ends, the middle remaining open, or at or near the middle the ends remaining open or alternately in sections, as indicated in Fig. 5; and right here I desire to have it understood that, instead of using two flexible valves p , with means for moving them in whole or in part away from each other, one of said plates may be flexible and movable, while the other may be perfectly stationary and immovable, in which case the stationary one would be made of sheet metal or similar substance. As the enamel leaves the valves p in a stream of the desired width, it flows between the rollers $M M$, which rollers are adjusted as far apart as desired to insure the discharge of the desired quantity of enamel during a given period of time. The enamel passing between these rollers is removed from their surfaces by the scrapers N , and flows from these scrapers upon the inclined smooth plate O , whence it flows in a continuous current upon the plates or articles carried by the apron f , said articles meanwhile moving with the apron from one sprocket-wheel to the other.

In order to regulate the distance which the liquid enamel shall fall from the plate O to the article to be enameled, the entire framing D , with its appurtenances, is made vertically adjustable by means of the screws E or similar mechanism. By this adjustment I am enabled to give a greater fall to thick enamel and a less great fall to liquid enamel. Any enamel which may have entered between plates or articles to be coated can be received in a vessel placed under the apron f and any adhering to the apron will be taken off by the brush j . The operation of the machine may be continuous, but can be interrupted whenever desired by a suitable belt-shipping apparatus applied to the belt g or to the belt for driving the shaft h .

Having thus described my invention, what I claim is—

1. The funnel F , having lower outlet-opening o , combined with the false perforated bottom G , placed above said outlet and having central semi-cylindrical depression, the rotary brush I , placed above said perforated false bottom, and the rotary agitator H , placed beneath said perforated false bottom and above said outlet-opening v , substantially as herein shown and described.

2. The funnel F , having outlet-opening o , combined with the lower converging and flexible valve-plates p , and means, substantially as described, for holding said valve-plates wholly or in part together or apart, as specified.

3. The combination of the funnel F, having outlet-opening o, with the flexible valve-plate p, link r, crank s, having counterpoise t, and with the shaft J, and means, substantially as described, for turning said shaft, and with the screw w for fastening the crank s and its counterpoise to the shaft J, substantially as and for the purposes described.
4. The combination of the funnel F, having outlet-opening o, with the flexible valve-blades pp, placed opposite each other, each as long as the outlet-opening, and with the short plates q, affixed to the outer sides of said flexible blades, links r, cranks s, counterpoises t, screws u, shafts J J on opposite sides of the funnel, worm-wheels z on said shafts, right and left screws y, and shaft L, all arranged for operation substantially as herein shown and described.
5. The combination of the funnel F and its outlet-opening o, and means, substantially as

described, for regulating the size of said opening, with rollers M M below said funnel, scrapers N, and inclined plate O below said roller, substantially as and for the purposes 25 herein shown and described.

6. The combination, in a machine for covering metal plates and other articles with enamel, of the endless apron f, and means, substantially as described, for supporting and 30 moving the same, with a funnel F, placed above said apron, and means, substantially as described, for regulating the discharge of liquid matter from said funnel, and with the inclined plate O interposed between the outlet-opening of said funnel and the endless apron f, substantially as herein shown and described.
